TYPEWRITING MACHINE

Johannes Krüger, Erfurt, Germany, assignor to
 Olympia Buromaschinenwerke A. G., Erfurt,
 Germany, a corporation of Germany

Application May 23, 1939, Serial No. 275,261
 In Germany June 24, 1937

2 Claims. (Cl. 197—22)

This invention relates to improvements in typewriting machines and particularly to an improved type action therefor.

The invention relates more particularly to typewriters of low and flat construction and a primary object thereof is to provide a simple type action lever system which will serve also to retain the type bars in a position of rest.

In carrying out the invention, the type bars are pivotally mounted in an inclined low positioned segment and bearings for intermediate levers of the key action are located on vertically spaced lines parallel to the axis of the paper roller and the levers and connections with the type bars are arranged in such a manner that with the parts in the position of rest, the arm of each intermediate lever connected by a pull rod to the heel of a type bar assumes a locking position beyond a projected straight line between its axis and the point of connection of the pull rod to the type bar. With this arrangement, the entire system is readily accessible for examination and repair and the objects of the invention are achieved with a minimum of structural changes.

Other objects and advantages of the invention will be apparent from the following detailed description and upon reference to the accompanying drawing which illustrates a preferred constructional embodiment of the invention and in which,

Fig. 1 is a sectional view through a typewriter embodying the invention, showing the parts of the type action in various positions,

Fig. 2 is a front elevation of the improved bearing bridge for the intermediate levers, and

Fig. 3 is an end view thereof.

Referring more particularly to the accompanying drawing, the type bars 5 are mounted in slots 6 of an inclined segment 7. The segment 7 is mounted low and in inclined position with respect to the roller platen 8. The heel portions of the type bars are pivoted in the slots 6 of the segment 7 by a pivot rod 9 and in the position of rest lie in a forwardly inclined position supported at their outer ends by a head rest 10.

The key levers 11 are pivoted at their rear ends on a shaft 12 and are guided in a vertical path by a guide comb 13 which includes also a stop 14 to limit upward movement of the key levers in the position of rest to which they are resiliently biased by tensile springs 15.

The type action connections between the key levers 11 and type bars 5 include intermediate levers arranged in groups transversely of the machine, there being two end groups and a central

group disposed on vertically spaced parallel axes, the end groups being located on the higher axis. The intermediate levers 16 of the central group are mounted in slots 17 formed in the lower edge of a transverse bridge member 18, the intermediate levers 16 being fulcrumed on a pivot rod 19 extending lengthwise of the rail and intersecting the slots 17.

The pivotal axis of the intermediate levers 16 is closer to one end thereof than to the other and the free end of the long rear arm 20 thereof is connected by a pull rod 21 to the heel of the type bar 5 at a point 22 which point in the position of rest is disposed below and rearwardly of the pivot 9. The end of the forwardly extending short arm 23 of the intermediate lever 16 is connected to the key lever 11 by a depending link 24.

The parts are arranged so that in the rest position the pivot point 25 between the rear arm 20 of the intermediate lever 16 and the pull rod 21 20 assumes a position beyond the line between the pivot points 9 and 19 and with the arm 19 and pull rod 20 disposed nearly parallel with the key lever.

Although rebound of the type lever would be 25 prevented by arranging the parts so that as the type lever returns to the rest position, the intermediate lever arm 20 and pull rod 21 assume an extended position in longitudinal alignment with each other, such an arrangement would not prevent rebound of the key lever from its stop. In order to prevent translation of the rebound movement of the key lever into movement of the type bar, the connections are arranged so that upon normal rebound of the key lever, the pivot point 25 will not be moved across the centerline C between the pivots 9 and 19, at which point motion would be imparted to the type bar. Thus, with the pivot 25 located beyond the centerline C, the rebound motion of the type bars and key levers 40 will be mutually repulsive.

In order that the intermediate levers 16a of the end groups associated with the type bars 5a mounted adjacent the ends of the segment 7 may be disposed in substantially the same relative position with respect to the type bars and key levers associated therewith as are the levers 16, the intermediate levers 16a of the end groups are mounted in slots 26 provided in the top of the rail 18. The intermediate levers 16a of the end groups are of the same construction as those previously described, being fulcrumed on a pivot rod 27 parallel to and vertically spaced above the pivot rod 19 and having oppositely disposed arms 20a and 23a connected by pull rods 21a to the 55

type bars 5a and to associated key levers by links 24a. The amount of vertical displacement between the pivot shafts 19 and 27 is preferably not as great as the displacement between the pivot points 9 and 9a of the center and end type bars mounted in the segment 7.

Referring more particularly to the transverse bearing bridge member 18 shown in Fig. 2, the latter comprises a long straight rail relatively flat 10 in cross-section and disposed on edge with its flat sides vertical. The rail is provided at opposite ends with flanges or ears 28 to facilitate mounting thereof between the sides of the machine frame, securing holes 29 being provided in these 15 flanges for suitable fastening elements. There are six slots 26 formed in the upper edge of the rail 18 adjacent each end for the reception of the intermediate levers of the end groups associated with the corresponding end groups of type 20 bars of the type segment. For the remainder of the length of the rail 18 the slots 17 are formed in the bottom edge thereof for the reception of the central group of intermediate levers associated with the intervening type bars. The pivot 25 shafts 19 and 27 upon which the intermediate levers are mounted preferably extend from end to end of the rail.

The bearing bridge could be formed of solid metal with the slots cut therein or could be 30 formed by a pressing operation with the slots pressed in at the one operation as desired.

While a preferred embodiment of the invention has been shown and described by way of illustration it is to be understood that modifications 35 of the details of construction may be resorted to without departing from the spirit of the invention within the scope of the appended claims.

I claim:

40 1. In a typewriter of flat construction, in combination, a paper roller, a rearwardly inclined type bar segment mounted forwardly of said paper roller with the upper edge thereof at substantially the same elevation as the axis of said 45 roller, a plurality of type bars pivotally mounted on said segment, a straight transverse bearing bridge rail mounted forwardly of said type bar segment and disposed substantially parallel to the axis of said paper roller at a height intermediate the upper and lower extremities of said type 50 bar segment, a plurality of key levers, operating connections between said key levers and said type bars comprising a plurality of two-armed levers pivotally mounted on said bearing bridge rail 55 along the length thereof, pull rods connected between one arm of said two-armed levers and said type bars and links connected between the other arm of said two-armed levers and said key levers, said bearing bridge rail being formed for a portion 60 of its length adjacent each end with a plurality of slots in the upper edge thereof providing a plurality of upstanding webs, a pivot rod extending through said webs parallel to the axis

of said rail on which pivot rod the two-armed levers associated with the end type bars on said segment are mounted, said bearing bridge rail being formed along the portion of its length intermediate the slots in its upper edge with a plurality of slots in the lower edge thereof providing a plurality of depending webs, a pivot rod extending through said depending webs on which pivot rod the two-armed levers associated with the intermediate type bars on said segment are 10 mounted, each of said two-armed levers having a position of rest in which the arm thereof connected with a type bar extends substantially in the direction of the pivot point of its associated type bar, the connection between each two-armed 15 lever and its associated pull rod being disposed when in the position of rest beyond a line drawn between the axis of the lever and the point of connection between the pull rod and its associated type bar.

2. In a typewriter of flat construction, a low placed rearwardly inclined type bar segment, type bars pivotally mounted in said segment, a key lever for each of said type bars, a straight transverse rail mounted forwardly of said segment at an elevation substantially intermediate the upper and lower extremities thereof, a plurality of upstanding parallel web members formed on the upper side of said rail adjacent each end thereof, a pivot rod extending through said web 30 members, a plurality of depending parallel web members formed on the lower side of said rail along the portion of the length thereof intermediate the innermost of said upstanding web members, a pivot rod extending through said depending web members, connections between said key levers and said type bars including a plurality of two-armed levers comprising end groups and a central group, a pull rod connecting the rear arm of each of said two-armed levers to the heel of 40 an associated type bar and a link connecting the front arm thereof to an associated key lever, the end groups of said two-armed levers being mounted respectively between the upstanding web members at opposite ends of said transverse 45 rail on the pivot rod extending therethrough and being connected to those type bars adjacent the ends of said type bar segment, the central group of said two-armed levers being mounted between the depending web members on the lower side of said rail on the pivot rod extending therethrough and being connected to those type bars in the central portion of said type segment, the rear arm of each of said two-armed levers in the position of rest extending substantially in the direction of the pivot of its associated type bar and with the point of connection of said pull rod therewith moved to a position beyond the centerline between the axis of the two-armed lever and the point of connection of said pull rod to said 55 type bar.

JOHANNES KRÜGER.
